UNITED STATES PATENT OFFICE.

EMILE MEYER, OF NEW YORK, N. Y.

DESIGN FOR WOVEN FABRIC.

Application filed August 10, 1926. Serial No. 18,664. Term of patent 14 years.

To all whom it may concern:

Be it known that I, EMILE MEYER, a citizen of the United States, and a resident of the city of New York, in the borough of Manhattan, county of New York, and State of New York, have invented a certain new, original, and ornamental Design for Woven Fabric.

Reference is to be had to the accompanying drawing, in which the figure represents a face view of a piece of fabric embodying my new design.

I claim:

The ornamental design for woven fabric as shown.

EMILE MEYER.
